United States Patent Office.

JAMES PRENTICE, OF NEW YORK, N. Y.

Letters Patent No. 61,099, dated January 8, 1867.

IMPROVEMENT IN EYE-GLASSES.

The Schedule referred to in these Letters Patent and making part of the same.

TO ALL WHOM IT MAY CONCERN:

Be it known that I, JAMES PRENTICE, of 164 Broadway, in the city, county, and State of New York, have invented a new and useful Improvement in Eye-Glasses; and I do hereby declare that the following is a full, clear, and exact description thereof, which will enable others skilled in the art to make and use the same, reference being had to the accompanying drawing, forming part of this specification.

The drawing represents a front elevation of this invention.

This invention relates to an improvement in that class of eye-glasses which are connected by a thin steel spring, and which, when to be used, are slipped over the nose, where they are held in position by the action of said spring.

Ordinary eye-glasses of this class have but a slender hold on the nose, their point of contact with the nose being reduced to a very small area, and on some noses said eye-glasses cannot be made to stay at all. This difficulty is obviated by the arrangement of two lugs projecting from the inner edges of said eye-glasses, and formed in such a manner that they increase the bearing surface of the edges of the eye-glasses on the nose, and said eye-glasses can be made to take a firm hold of any nose whatever.

A A represent a pair of eye-glasses which are connected by the spring B. From the inner edges of said eye-glasses project the lugs a a, which are made in such a shape that they increase the bearing surface of the eye-glasses on the nose.

When placed on the nose, my eye-glasses take a firm hold and are not liable to drop off spontaneously; they do not produce a pain on the nose, and they can be readily attached to noses of any form or description.

Having thus described my invention, I claim as new, and desire to secure by Letters Patent—

The nose-pieces a a on the eye-glasses A A, extending from a point below the centre of the glass to a point above said centre, with gradually increasing width, in order to conform to the anatomy of the nose, as herein shown and described and for the purpose specified.

JAMES PRENTICE.
